(57) **CLAIM**

The ornamental design for a body wallet, as shown and described.

DESCRIPTION

FIG. 1 is a perspective view of our body wallet showing my new design, the broken lines showing a belt and top of a skirt or trousers are for illustrative purposes only and form no part of the claimed design;

FIG. 2 is a front elevational view thereof;

FIG. 3 is a right side elevational view thereof, the left side being identical;

FIG. 4 is a rear elevational view thereof;

FIG. 5 is a top plan view thereof;

FIG. 6 is a bottom plan view thereof;

FIG. 7 is an enlarged cross-sectional view taken along line 7—7 of FIG. 2; and,

FIG. 8 is a perspective view of a second embodiment of FIG. 1, the remaining views being the same as that shown in FIGS. 2—7 with the exception of the transparency.
